UNITED STATES PATENT OFFICE.

JEREMIAH KELLER, OF SANDUSKY, OHIO.

GRAIN-BINDER.

SPECIFICATION forming part of Letters Patent No. 461,794, dated October 20, 1891.

Application filed December 19, 1887. Serial No. 258,265. (No model.)

To all whom it may concern:

Be it known that I, JEREMIAH KELLER, a citizen of the United States, residing at Sandusky, in the county of Erie and State of Ohio, have invented certain new and useful Improvements in Grain-Binders, of which the following is a specification, reference being had therein to the accompanying drawings.

This invention relates to new and useful improvements in grain-binders; and the invention consists in the improved construction, arrangement, and combination of different parts, as hereinafter more fully described.

15 In the drawings which accompany this specification, Figure 1 is a rear elevation of the binder in connection with the harvester. Fig. 2 is a perspective view of the binder. Fig. 3 is a front elevation of the binder. Fig. 20 4 is a similar elevation, with the parts at a different stage of the operation. Fig. 5 is a plan of the U-frame, which carries the knot-tying mechanism. Fig. 6 is a perspective view of the breast-plate and portion of the 25 knot-tying mechanism. Fig. 7 is a plan of the breast-plate, with the stationary and movable twine-guide. Fig. 8 is a side elevation of the knot-tying mechanism at a certain position in its operation. Fig. 9 is a similar 30 view, including the binding mechanism. Fig. 10 is a perspective view of the cam-disk, which appears in the knot-tying mechanism. Fig. 11 is a side view thereof. Fig. 12 is a detached perspective view of the knotter. Fig. 13 is a detached perspective view of the oscillating twine-holder. Fig. 14 is a bottom view of the same. Fig. 15 is a top plan thereof. Fig. 16 is a cross-section of the same. Fig. 17 is a detached perspective view of a part of 40 the mechanism which operates the movable twine-guide. Fig. 18 is a perspective view of a portion of Fig. 17. Fig. 19 is a cross-section of Fig. 18. Fig. 20 is a detached side elevation of the tension device for the 45 compressor-arm. Fig. 21 is a perspective view of one of the levers of the tension device shown in Fig. 20. Fig. 22 is a detached view of the other lever of said tension device. Fig. 23 is a detached view of the crank-lever on the bind- 50 er-shaft with the trip-arm attached to it. Fig. 24 is an elevation of the movable part of the clutch. Fig. 25 is a perspective view of the movable part of the clutch with the dog detached. Fig. 26 is a perspective view of the

dog. Fig. 27 is a detail showing the knotter 55 in operation.

In the drawings all like parts are referred to by the same numerals, of which—

1 is the binding table or deck, on which the grain is delivered from the harvester in the 60 usual manner.

2, Fig. 9, is the oscillating binding-arm.

3 is the binder-arm shaft.

4 is an ear formed on the hub of the binder-shaft.

5 is an arm hinged at one end to the ear 4 and having secured to it near the other end the compressor 6.

7 is a link pivotally secured at one end to the arm 5 and at the other end to the free end 70 of the crank-arm 8 on compressor-shaft 9, which is journaled in suitable bearings below the binding-platform, and has secured to its free end the crank 10, as shown in Figs. 3 and 4, and this crank has an arm or stop 90, which 75 normally rests against the frame, as shown in Fig. 3.

11 is a connecting-rod pivotally secured at one end to the crank 10 and at the other end to the compressing-lever 12, which is fulcrumed at 13 to the frame, and is provided with a toe 35 at its free end, and has pivotally secured at 14 the tension-rod 15, upon which is sleeved the compressor-spring 16, adjustably secured thereto by suitable nuts and 85 washers 17.

18 is another lever fulcrumed on the same fulcrum 13 with the compressing-lever, but adapted to move independently thereof. This lever has three arms. The arm 19 bears a 90 roller 20. The arm 21 terminates in an eye 22, through which the tension-rod 15 passes loosely and which serves as an abutment for the compressor-spring 16. Between the arms 19 and 21 is placed the curved guide-bar 23, 95 on which there is a projecting top 24, Fig. 21, against which the toe 35 is adapted to bear. 25 is the third arm of this lever, and this has formed in its free end the eye 26, the rest 27, the abutment 28, and the stop 29.

30 is a movable stop pivotally secured to the eye 26 on the lever 18, and this stop carries at one end the roller 31, and to its heel it has hinged the tension-rod 32, which has sleeved upon it the spring 34, and projects through 105 the abutment 28.

36 is a U-shaped frame rigidly secured to the binder-frame and for the purpose of sup-

porting the knotter mechanism, as in the ordinary construction of binder. The overhanging arm of the U-shaped frame is hollow and supports in suitable bearings therein the operating-shaft 37 of the knotter mechanism. To the inner free end of this shaft is secured the cam-wheel 60, and to its outer free end is secured the sprocket-wheel 38, which latter is provided with the cam 39, 10 against the face of which the rollers 31 and 20, heretofore described, bear.

40 is a sprocket-chain which passes around the sprocket-wheel 38 and around the little idler-sprocket 41, carried upon the arm 42, 15 which is hinged upon the end of the packer-shaft 91, and is adjustably secured by the nut 43 to the slotted guide-bracket 44. The lower portion of this sprocket-chain is guided on the under side of the curved guide-flange 45, 20 which is formed on the arm 42, and the upper portion of the sprocket-chain passes around the under side of the sprocket-wheel 46, which is loosely sleeved upon the packer-shaft 91. This sprocket-pinion 46 forms part of a clutch 25 shown in Figs. 24, 25, and 26, of which the driving-head 47, forming one part, is fast on the packer-shaft, and carries two pins 48, either one of which is adapted to normally engage with the arm 49 of the dog 50, which 30 latter is pivotally secured to the pin 51 of the loose sprocket-pinion 46. This dog has an arm 52, which normally rides on the hub of the sprocket-pinion, and also an arm 53, which projects outwardly and is adapted to strike 35 in the operation of the machine the tripping-arm 54 when the latter is in the position shown in Fig. 3, and thereby trip the clutch-dog 50 out of gear. This tripping-arm 54 is sleeved upon the binder-arm shaft 3 (see Fig. 40) near the free end thereof, in proximity to the crank 55, so as to rest with its projecting flange 56 upon said crank, which is fast upon the binder-shaft. The tripping-arm has a yielding connection with the crank 55 by 45 means of the spring 57, and a connecting-rod 92, Fig. 3, pivotally connects it with the crank 93 of the tripping-shaft 94, which latter is secured in suitable bearings upon the binder-platform and carries the yielding arm 95, 50 which is adjusted above the binding-platform in an inclined position, so as to be lifted up on its free end when the bundle has attained the proper size. The free end of the crank 55 has hinged to it one end of the connecting-rod 58, the other end of which engages with 55 the wrist-pin 59 on the sprocket-wheel 38.

The knotter-operating cam-wheel 60 has formed around its periphery the annular delay-flange 64, and this is cut-away at three 60 points, marked 61, 62, 63, in Fig. 10. The cut-away portions 61 and 62 are formed by cutting the delay-flange away upon the outer periphery, and the cut-away portion 63 is formed by cutting away the inner periphery 65 of the delay-flange. An oblique cam 61 is placed on the outer periphery of the delay-flange between the cut-away portions 61 and

62, and cogs 68 are placed upon the side of the cam-disk in proximity to and in relation with the cut-away portion 63 of the delay-flange, and the cut-away end 65 of the delay-flange is formed on an incline. 70

66 is a cam-groove formed in the body of the disk, and this cam-groove is partly concentric. 75

67 is a roller secured upon a wrist-pin on the wedge-shaped body formed between the eccentric portions of the cam-groove.

69 are ejector-arms carried by the shaft 37.

The knotter consists of the frame 70, which 80 is provided with the hub 71, by means of which it is sleeved upon the shaft 37, and upon this hub is formed a gear-tooth 72.

73 is the knotter-shaft, upon which is secured the knotter-pinion 74 and the head 75. 85 This knotter is of the usual bill shape and has a movable jaw 76, which moves parallel with the fixed jaw 77, formed integrally with the knotter-head. The knotter-shaft 73 is hollow, and through it passes a stem 96, to 90 one end of which is secured the movable jaw 76 of the knotter-bill, and to the other end of which is secured an anti-friction roller 78, which bears on the cam 79, formed on the knotter-frame. 95

80 is a spring pressure-foot bearing against the free end of the stem with the tension of the spring 81.

82 and 83 are contiguous flat delay-faces formed partly on the frame of the knotter 100 and partly on the knotter-pinion, as shown.

84 is a support or bracket for supporting some of the operating parts of the knotter mechanism. This bracket is shown in Figs. 5 and 16. It has two ears 85 86, by means of which it is sleeved upon the hub 71 of the knotter-frame, and two legs 87 88, by means of which it is secured to the breast-plate 89, and thereby forms a rigid support. The lower end of the leg 87 of this bracket has integrally formed with it the stationary twine-rest 97 and the twine-guide 100, Figs. 6 and 7, which by its rounding configuration guides the twine from the straight portion 101 of the needle-arm slot of the breast-plate into the 110 lower curved end 102 thereof. 115

103 is a short shaft journaled in suitable bearings formed in the support 84, and this shaft is provided upon its inner free end with the short crank 104, which carries the roller 105, which engages into the cam-groove 66 of the cam-wheel 60. Upon the shaft 103 is supported, as shown in Figs. 17 and 18, a hollow sleeve made in two parts 106 and 107, the former being fast and the latter being loose 125 upon said shaft, and the meeting edges of these two parts have projecting lugs or teeth in the manner of clutches to engage with each other, but allowing a limited loose play to the part 107, and a coiled spring 108 is 130 sleeved upon them with one end made fast to one part and the other made fast to the other part. The loose part 107 is provided with a crank 109, to which is pivotally se-

cured the rod 110, Figs. 5, 6, and 7, the other end of which is pivotally secured to the heel of the tucker 111. This tucker is fulcrumed on a pin 112 between the breast-plate and the 5 foot 87 of the support 84, as shown in Fig. 5, and has a free play forward from its normal position, (shown in Figs. 5, 6, and 7,) where it rests against the stop 113.

From the shaft 103 is suspended the oscillating cord-holder frame (shown detached in Figs. 13, 14, and 15) by means of the hangers 114 and 115, which have eyes 116 and 117 formed on their upper ends, through which the shaft 103 loosely passes. The hangers carry the 15 annular grooved frame 118, in which is removably secured the rotary ring 119, provided upon its inner edge with a series of notches 120 and upon the upper side with a series of lugs 121. A shoe 122 embraces the inner 20 edge of the rotary ring 119 by means of the groove 123 cut therein, and this is secured to an arm 124, pivotally secured at 125 to the cord-holder frame and provided with the spring 126, Fig. 14, the tension of which keeps the 25 shoe in its engagement with the edge of the ring. The cord-holder is further provided with a knife 127, (shown in Fig. 15,) attached to the end of an arm 128, which is pivotally secured at 129 to the under side of the cord- 30 holder frame and carries the roller 130, which is struck periodically by the portion 65 of the cam-wheel to force its cutting-edge against the cord to sever the same. The tension of the spring 131 tends to keep said arm in its 35 normal position. The flange on the cam-wheel engages between the lugs on the rotary ring and locks the same until the cut-away portion of the wheel arrives at this point, when the ring is unlocked. The inclined portion 61' is then brought into contact with the 40 lugs and forces the ring one step forward. The rotary ring 119 is prevented from turning backward by means of a locking-pawl 132, Fig. 15, which is adapted to engage with 45 the lugs 121, thereby preventing any sudden jar from altering the position of the ring. The cord-holder is free to have an oscillating movement on the shaft 103, from which it is suspended, and this movement is brought 50 about by means of a roller 133, carried by an adjustable extension 134 of the arm 115 and engaging into the cam-groove 66 of the cam-wheel.

To the support or bracket 84, before described, is pivotally secured a bell-crank 137, one arm of which carries a roller 135, Fig. 6, and a lug 136, the former of which engages into the cam-groove of the cam-wheel, while the latter is adapted to be engaged by the 55 roller 67, carried by the cam-wheel. The other arm of the bell-crank 137 has a notch 138, into which the cog-tooth 72 on the knotter-frame engages.

In practice, the parts being constructed and 60 arranged as described, it will be seen that the operation of the binding mechanism is derived from the packer-shaft 91, which, as in

the usual practice, is provided with continuous motion derived from the operating mechanism of the harvester in any suitable manner—as, for instance, shown in the diagram Fig. 1, where a sprocket-pinion 139 is secured upon the rear end of the packer-shaft and around which the sprocket-chain 140 passes, which conveys the motion from the operating 70 parts of the harvester. The grain being delivered upon the binding-platform by the usual elevating devices, it is collected by the packers (which are of known construction and operation) against the compressor-arm. As 80 the bundle is forming, the free end of the yielding arm 95 is gradually lifted up by the increasing gavel until by means of the connections described (which are adjustable for the purpose of regulating the size of the bundle) the trip-arm 54 is lifted up sufficiently to 85 release it from its engagement with the arm 53 of the dog of the trip-clutch. This movement throws the trip-clutch into gear and motion will be imparted immediately to the 90 sprocket-chain 40 by means of the sprocket-wheel 46. The sprocket-chain imparts motion to the sprocket-wheel 38, which thereupon begins to revolve the shaft 37, upon which it is fast, and also to convey the motion 95 to the binder-arm shaft by means of the connecting-rod 58 and crank 55. The sprocket-wheel 38 makes one complete revolution, and this motion produces the necessary oscillation of the binder-shaft to carry the binder-arm 100 sufficiently forward to lay the twine into the cord-holder and then back again to its normal position. This rearward oscillation carries the tripping-arm 54 back to its normal position, where it will trip the clutch again and arrest 105 the further movement of the binder mechanism. The movement of the binder-arm also actuates the compressor-arm to compress the bundles, the normal position of the compressor-arm being shown in dotted lines in Fig. 9, while 110 the full lines show the position it assumes while the binder-arm has finished its forward movement. In this position it is acted on by the tension of the compressor-spring 16, which is held between the two abutments 17 115 and 22. This abutment 22 is maintained by the lever 18, which, as described, carries the roller 20, and as long as this roller travels on the circular portion of the cam 39 (which it does until the bundle is tied) this abutment 120 remains stationary. The abutment 17 yields, however, and by means of the connection described the compressor-arm is permitted to yield to the force of compression on the bundle, and the abutment 17 will approach the 125 abutment 22 until the pressure of the bundle is equal to the tension of the compression-spring. Thus by adjusting the abutment 17 the amount of yield of the compressor-arm under the force of compression on the bundle, 130 as produced by the relative opposite movements of the binder-arm and compressor, may be adjusted to any desired degree. In Fig. 4 the action of the compression on the com-

pression-spring is illustrated by a different position of the toe 35 from the normal position in Fig. 3. As long as the roller 20 travels on the circular portion of the cam 39, the compression is maintained; but at the time the tying of the bundle is completed the roller 20 arrives at the end of the circular portion of the cam and is free to oscillate sufficiently to permit the compressor-arm to move out of the way below the binder-platform to permit the ejector to throw the bundle off. This withdrawal of the compressor-arm is brought about by the action of the movable stop 30, the spring 34 of which is under tension, owing to its roller 31 being forced to ride on the circular portion of the cam. (See Fig. 4.) This tension causes the lever 18 to oscillate as soon as it is free to do so, and thereby to carry by means of the different connections the compressor-arm out of the way until the roller 20 is again carried on to the circular portion of the cam 29 and the parts restored to their normal position, while the roller 31 of the movable stop drops onto the radial portion 140 of the cam-guide, and thereby forms a stop, which prevents a retrograde movement of the parts and takes up the slack in the clutch.

The operation of the knotter mechanism begins with the movement of the tucker, which is actuated by the roller 105, which is the first one to enter the eccentric portion of the groove in the cam-wheel 60. This movement causes the tucker to oscillate on its pivot, so as to cause its hook-shaped free end to engage upon the twine, tuck it into the twine-rest 97, so that it will be in proper position for the knotter-head to seize it. As shown in Fig. 9, the binder-arm prevents the tucker from withdrawing to its normal position before the binder-arm itself withdraws, and to permit the tucker to delay its reverse movement to the normal position I have constructed the yielding connection shown in Figs. 17, 18, and 19, which permits the roller 105 to return to its normal position under the action of the cam-groove 66, while the tucker retreats to its normal position by the tension of the spring 108, as soon as the tucker is free to retire, when the binder-arm gets out of the way. The twine is carried by the head of the binder-arm through the annular cord-holder, which has one of its notches 120 in proper position to receive the twine. The cam-wheel 60, engaging with its peripheral flange between two adjoining lugs on the rotary annular ring, keeps the same locked until the movement of said cam-wheel brings the cut-away portion between the two lugs, unlocks the ring, and permits the incline 61' to engage the next lug and to turn the ring one step, the locking-pawl arresting it in such position. By this movement the twine delivered by the binder-arm into one of the notches is carried thereby until it is nipped by the shoe. Now the knotter begins to operate in the usual manner by the engagement of the cogs 68 on the

cam-disk with the knotter-pinion 74, which is now free to revolve on account of the delay-flange 64 being cut away at 63. To provide the necessary slack in the twine for the formation of the loop, the cord-holder is now oscillated toward the knotter-head by means of the roller 133, which now enters the eccentric portion of the cam-groove in the cam-wheel. The second cut-away portion 62 on the peripheral flange of the cam-wheel is made to permit the knife 127 to keep out of the way of the twine until its roller 130 is struck by the corner 65 on the cam-wheel, which oscillates it sufficiently to cut the twine. The angular position of the twine as held by the cord-holder helps to guide the twine into the jaw of the knotter, and the cord-holder is at its nearest approach to the knotter-head at the time it delivers the twine into the jaw of the same. After the twine is cut the twine-holder is moved back to its normal position. The knotter-head makes two revolutions. At the first it forms the knot upon its head, and during its second revolution it strips the knot. This is accomplished by the roller 67 on the cam-wheel striking the lug 136 on the bell-crank 137, thereby causing the knotter-frame to oscillate and free itself from the knot. This movement is accomplished much quicker by means of the parts described than it would be accomplished by the roller 135 in following the eccentric portion of the cam-groove, which movement would be too slow on account of the revolving motion of the knotter-head, which demands a quick movement just at the time when the jaws of the knotter-head are turned toward the bundle. However, the roller 135 returns the knotter again to its normal position. To permit the roller 67 on the cam-wheel to effect the oscillation of the knotter-head, the cam-groove is partly cut away to permit the roller 135 to get temporarily outside the cam-groove.

What I claim as my invention is—

1. In a grain-binder, the combination of two sprocket-gears, one upon the knotter-shaft and the other an idler, a belt supported by said sprockets with a third sprocket-gear mounted upon the packer-shaft and engaging the outside of said belt and serving to drive the same, substantially as described.

2. In a binding mechanism as a means for conveying motion in opposite directions directly from the packer-shaft to the actuating-shaft of the knot-tying mechanism, the combination, with the sprocket-wheel 38 on the actuating-shaft, of the knot-tying mechanism, the sprocket-wheel on the packer-shaft, and the adjustable idler-pinion 41 above the packer-shaft, of the sprocket-chain 40, passing around the sprocket-wheel 38 and idler-pinion in the same direction, and in engaging one side only of the pinion on the packer-shaft and with its lower portion hanging slack, and a guide for the slack portion of the chain, substantially as described.

3. The combination, with the actuating-

shaft, of the knot-tying mechanism, the sprocket-wheel 38 secured thereon, the idler-pinion 41, the sprocket-chain 40, passing around said sprocket-wheel and idler-pinion, 5 the sprocket-pinion on the packer-shaft engaging with its lower face in the upper ply of said sprocket-chain and transmitting motion thereto, and the curved guiding-flange for the slack lower ply of said chain, substantially as described.

4. In a grain-binding mechanism, the combination, with a revolving packer-shaft or other continuously-revolving shaft, of a trip-clutch on said shaft, one member of which 15 contains a sprocket-pinion loosely sleeved thereon, an idler sprocket-pinion, a sprocket-wheel on the actuating-shaft of the knotter mechanism, and a sprocket-chain around said sprocket-wheel and the idler sprocket- 20 pinion and engaging one side only of the sprocket-pinion on the packer-shaft and deriving its motion direct from the sprocket-pinion of the clutch, substantially as described.

25 5. In a grain-binding mechanism, the combination, with a revolving packer-shaft or other continuously-revolving shaft, of a trip-clutch on said shaft, the loose member of which contains a sprocket-pinion, an idler sprocket-pinion, a sprocket-wheel on the actuating-shaft of the knotter mechanism, a sprocket-chain around said sprocket-wheel and the idler sprocket-pinion and engaging with one side only of the sprocket-pinion of 30 the clutch, a crank on the binder-shaft, and a connecting-rod from said sprocket-wheel to the crank on the binder-shaft, all substantially as described.

35 6. In a grain-binding mechanism, the combination, with a revolving packer-shaft or other continuously-revolving shaft, of a trip-clutch on said shaft, the loose member of which contains a sprocket-pinion, an idler sprocket-pinion, a sprocket-wheel on the actuating-shaft of the knotter mechanism, a sprocket-chain around said sprocket-wheel and the idler sprocket-pinion and engaging with one side only of the sprocket-pinion of the clutch, a crank on the binder-shaft, a 40 crank-rod from said sprocket-wheel to the crank on the binder-shaft, a tripping-arm loosely sleeved upon the binder-shaft and carried by the crank on the binder-shaft and having a flexible connection therewith, all substantially as described.

45 7. In a grain-binding mechanism, the combination, with a revolving packer-shaft or other continuously-revolving primary shaft, of a trip-clutch on said shaft, the loose member of which contains a sprocket-pinion, an idle sprocket-pinion adjustably secured to the binder-frame, a sprocket-wheel on the actuating-shaft of the knotter mechanism, a sprocket-chain around said sprocket-wheel and the idler sprocket-pinion and engaging 50 with one side only of the sprocket-pinion of the trip-clutch, a crank on the binder-shaft, a

crank-rod from said sprocket-wheel to the crank on the binder-shaft, a tripping-arm loosely sleeved upon the binder-arm and 55 adapted to be carried by the crank on the binder-shaft, a flexible connection between said tripping-arm and crank on the binder-shaft, a vertically-yielding arm adjusted above the binder-platform, and operating 60 connection between said yielding arm and the tripping-arm, substantially as described.

65 8. The combination, in a grain-binder, of the operating-shaft 37 of the knot-tying mechanism, the sprocket-wheel 38 secured thereon, 70 the idler sprocket-pinion 41, the trip-clutch secured to the packer-shaft and having a sprocket-pinion 46, which forms the loose member thereof, and the adjustable plate 42, adjustably sleeved upon the shaft of the trip-clutch and provided with the flange 45, and carrying the idler sprocket-pinion, substantially as described.

75 9. The combination, with the sprocket-pinion 46 on the packer-shaft or other continuously-revolving primary shaft of a binding mechanism, of the sprocket-wheel 38, the sprocket-pinion 41, the sprocket-chain 40, the radially-adjustable plate 42 carrying the sprocket-pinion 41, and the guide-flange 45 on 80 the plate, all arranged substantially as described.

85 10. In a grain-binder, the combination, with the compressor secured to the free end of an arm one end of which is hinged to the heel 90 of a needle-arm, of a yielding support for the free end of said arm consisting, substantially, of a rock-shaft provided with two cranks, one being connected by means of a link to the free end of the arm carrying the compressor, 100 and the other being connected by means of a link to one end of a lever, the opposite end of which carries the abutment of a compressor-spring, the lever 18 carrying an abutment, a compressor-spring interposed between said 105 abutments, and a cam on the shaft of the knot-tying mechanism for moving the lever 18, substantially as described.

90 11. In a grain-binder, the combination, with the needle-arm, of the compressor 6, the arm 115 5, hinged to the heel of the needle-arm, the rock-shaft 9, having rock-arms 8 and 10, the link 7, connecting the rock-arm 8 with the arm carrying the compressor, the lever 12, pivotally secured to the frame of the binder, the 120 link 11, connecting said lever with the rock-arm 10, the tension-rod 15, carried by said lever and having the abutment 17, the lever 18, carrying the abutment 22, the compressor-spring interposed between said abutment and 125 the abutment 17, the roller 20, carried by the lever 18, the cam 39, carried by the operating-shaft of the knot-tying mechanism, and the movable stop 30, pivotally secured to the heel of the lever 18 and having the tension-spring 130 34, all arranged to operate substantially as described.

12. In a grain-binder, the combination, with the compressor and its operating mechanism,

substantially as described, of a yielding support in said mechanism, consisting of the levers 12 18, secured on a common fulcrum, the stop 35, eye 14 on the lever 12, the tension-rod 15, the abutment 17, formed on the end of the tension-rod, the eye 22 on the lever 18, the roller 20, the movable stop 30, pivotally secured to the lever 18, the tension-rod 32, spring 34, and roll 31 of the movable stop, and the cam 39, carried by the revolving shaft of the knot-tying mechanism, substantially as described.

13. In a knot-tying mechanism, a twine-holder consisting of a ring-frame secured in bearings and adapted to oscillate, a notched annulus loosely secured in said frame, a grooved shoe engaging with the inner edge of the annulus, and actuating mechanism for imparting an oscillating movement to the frame and a partial rotation to the annulus at each tying operation, substantially as described.

14. In a knot-tying mechanism, the combination of a twine-holder consisting of a ring-frame, an annulus loosely secured therein and having a series of notches upon its inner edge and a series of lugs on its face, a grooved shoe engaging with the inner edge of the annulus, and a rotating disk having a cam adapted to engage with said lugs and impart a partial rotation to the annulus at each revolution of the disk, substantially as described.

15. The combination, in a twine-holder, of a ring-frame, an annulus loosely secured in said frame and having a series of notches on its inner face, a grooved shoe adapted to engage with the inner edge of the annulus, a series of lugs on the annulus, a revolving disk on the actuating-shaft of the knot-tying mechanism, a cam on the periphery of the disk adapted to engage with said lugs and impart a partial rotary movement to the annulus at each revolution of said disk, and a locking-flange on said disk adapted to engage with the lugs on the annulus to lock the same in position, substantially as described.

16. In a knot-tying mechanism, the combination, with a twine-holder, consisting of a ring-frame, a notched annulus loosely secured in said frame, a grooved shoe engaging with the inner edge of said annulus, a series of lugs on the annulus, a revolving disk having a segmental flange on its periphery adapted to lock and unlock the annulus, a cam on said disk to impart a partial rotation to said annulus, of a knife carried by an arm pivotally secured to the ring-frame of the twine-holder, a roller or other projection on said arm, and a cam on the disk adapted to oscillate said knife, all substantially as described.

17. The combination of the ring-frame 118, the annulus 119, loosely secured therein, the notches 120 in the inner edge of the annulus, the grooved shoe 122, secured to the pivotal arm 124, the spring 126, the series of lugs 121, the revolving disk 60, having a peripheral

segmental flange adapted to lock and unlock the annulus, and the cam 61, all arranged to operate substantially as described.

18. The combination of a twine-holder consisting of a ring-frame oscillatingly supported in bearings, a notched annulus loosely secured in said frame, a grooved shoe engaging with the inner edge of said annulus, a series of lugs on the annulus, a revolving disk having a segmental flange adapted to lock and to unlock the annulus, a cam on said disk adapted to impart a partial rotary motion to the annulus, a cam-groove in said disk, and a roller carried by the oscillating ring-frame and engaging into said cam-groove, all arranged to operate substantially as described.

19. The combination of the oscillating knotter-frame 70, sleeved upon the operating-shaft and carrying a revolving knotter, substantially as described, the tooth 72 on said knotter-frame, the bell-crank 137, stationarily pivoted and carrying the roller 135, and the notch 138, the disk 60, secured upon said operating-shaft, and having the cam-groove 66 engaging with the roller 135, all substantially as described.

20. The combination, with the oscillating knotter-frame 70, sleeved upon the operating-shaft of the knotter mechanism and carrying a revolving knotter, substantially as described, of the tooth 72, formed on said knotter-frame, the bell-crank 137, stationarily pivoted, the roller 135, notch 138, and lug or projection 136, carried by said bell-crank, the disk 60, secured upon the operating-shaft of the knotting-mechanism, the cam-groove 66, formed in said disk and engaging the roller 135, and the roller 67, carried by said disk, all arranged to operate substantially as described.

21. In a knot-tying mechanism, the combination, with a revolving disk secured upon the operating-shaft of the knot-tying mechanism, of a cam-groove formed in said disk, an oscillating knotter-frame sleeved upon said operating-shaft and carrying a revolving knotter, substantially as described, a bell-crank lever carrying a roller engaging into the cam-groove of the disk, operating connection between said bell-crank and the knotter-frame to hold said frame in position and oscillate it, an oscillating twine-holder, substantially as described, a roller carried by the frame of the said twine-holder and engaging into said cam-groove, the disk to oscillate said twine-holder, and a roller engaging into said cam-groove of the disk and having actuating connection with a tucker, all substantially as described.

In testimony whereof I affix my signature in presence of two witnesses this 1st day of August, 1887.

JEREMIAH KELLER.
